(57) **CLAIM**

We claim the ornamental design for a front combination lamp for an automobile thereof, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view for a “front combination lamp for an automobile” showing my new design,
FIG. 2 is a front view thereof,
FIG. 3 is a rear view thereof,
FIG. 4 is a top view thereof,
FIG. 5 is a bottom view thereof,
FIG. 6 is a left-side view thereof,
FIG. 7 is a right-side view thereof; and,
FIG. 8 is a perspective view of a second embodiment thereof, wherein the only difference resides in the translucent lens.
